UNITED STATES PATENT OFFICE.

HARRY M. SEAGERS, OF GENEVA, AND CHARLES D. CORWIN AND ALONZO B. ELY, OF GROTON, NEW YORK, ASSIGNEES TO HULSE MANUFACTURING COMPANY, OF GENEVA, NEW YORK, A CORPORATION OF NEW YORK.

EMBOSSING APPARATUS.

Application filed June 24, 1922. Serial No. 570,589.

To all whom it may concern:

Be it known that we, HARRY M. SEAGERS, a citizen of the United States, and resident of Geneva, in the county of Ontario and State of New York, and CHARLES D. CORWIN and ALONZO B. ELY, citizens of the United States, and residents of Groton, in the county of Tompkins and State of New York, have invented certain new and useful Improvements in Embossing Apparatus, of which the following is a specification.

This invention relates to improvements in embossing apparatus, and more particularly to apparatus for punching characters, ornamental figures and the like from colored paper and forcing the same into a cardboard backing to form embossed signs, display and advertising cards, and the like.

The invention has for its principal objects to provide an inexpensive, compact and efficient press adapted to develop a very high pressure, with slight effort on the part of the operator, for forcing the punching type through the colored paper and into the cardboard backing; to provide improved type and type-holders so constructed that the type can only be inserted in the holders in upright position, thus avoiding accidental inversion of some of the type during the type-setting operation; to provide an improved carriage or support for the type-holders and the colored paper and cardboard whereby the paper, cardboard and type may be clamped together and shifted between the bed and platen of the press; to provide simple means for holding the type-holders in various adjusted positions on the carriage; to provide simple and inexpensive type-holders and locking and spacing devices for retaining the type in proper position in the holders; to provide means for detachably holding type, or rows of type, in parallel, staggered, or angularly disposed lines on the carriage or support; to provide simple means for slidably supporting the type carriage on the press; and to provide efficient means for regulating the depth of penetration of the punching type into the cardboard backing.

To the foregoing and other ends, which will hereinafter appear, the invention consists in the improved construction of devices,

the arrangements of parts, and combinations of elements, set forth in the following description and particularly pointed out in 55 the appended claims.

In the accompanying drawings, wherein is illustrated one satisfactory and desirable embodiment of the invention, and in which similar reference characters designate corresponding parts throughout the several views:

Fig. 1 is a front elevation of the apparatus;

Fig. 2 a side elevation thereof showing 65 the sliding carriage drawn forward;

Fig. 3 a perspective view of the cam for operating the vertically shiftable bed of the press;

Fig. 4 a fragmentary vertical section 70 taken on the line 4—4 of Fig. 1 showing the carriage shifted to position the type, colored paper, and cardboard backing between the bed and platen of the press ready for the squeezing operation;

Fig. 5 a view similar to Fig. 4 showing the positions of the parts at the end of the squeezing movement;

Fig. 6 a detail sectional view of the cam;

Fig. 7 a detail view showing the inner 80 face of the hand-lever socket;

Fig. 8 a detail section on the line 8—8 of Fig. 10 showing the means for limiting the throw of the hand-lever;

Fig. 9 a detail view of the side face of 85 the press adjacent the socket end of the hand-lever;

Fig. 10 a vertical sectional view on the line 10—10 of Fig. 4;

Fig. 11 a horizontal sectional view on the 90 line 11—11 of Fig. 10;

Fig. 12 a detail perspective view showing one end of one of the sets of antifriction rollers;

Fig. 13 a plan view of the carriage with 95 a group of three type-holders arranged thereon as shown in Figs. 2 and 4;

Fig. 14 a section on the line 14—14 of Fig. 13 showing the colored paper and cardboard backing in place on the type;

Fig. 15 a detail sectional view on the line 15—15 of Fig. 19 showing one of the short type-holders and the means for attaching it to the carriage.

Fig. 16 a detail transverse section through one of the type-holders showing one of the blocks or plates used to hold the type against movement longitudinally of the holder and also to space words or groups of type in the holder;

Fig. 17 a detail transverse section through one of the type holders and type showing the cutting edges of the type forced through 10 the colored paper into the cardboard backing;

Fig. 18 a plan view of one of the type;

Fig. 19 a plan view of the carriage showing an arrangement of short and long type-holders thereon;

Fig. 20 a detail section on the line 20—20 of Fig. 19 showing one of the adjustable connections between a card-holder and the carriage;

20 Fig. 21 a sectional view on the line 21—21 of Fig. 14;

Fig. 22 a detail perspective view showing one of the clamping bolts and nuts employed to attach the card-holders and the short or 25 angularly adjustable type-holders to the carriage;

Fig. 23 a detail perspective view showing one end of the long type-holders; and

30 Fig. 24 a sectional view on the line 24—24 of Fig. 21.

The pedestal or base 1 of the press comprises a hollow metal casting, having a flange 2 held to a floor or other foundation by bolts 3, and also provided with an integral top 35 plate or platform 4 upon which the bottom wall 5 of the main body portion of the press is detachably but rigidly held by bolts 6 and nuts 7. The press body is attached to the pedestal by first inserting the heads of bolts 40 6 in the wider outer ends of "key-hole" channels or slots 8 in the bottom wall 5, then shifting the bolts laterally toward each other until their shanks engage in the narrow throats 8^a of the undercut portions of 45 the slots, seating the press body on the top plate 4 with the bolts passing through bolt holes 9 in said plate, and finally screwing on the nuts 7. The press body is thus held against movement in any direction relatively 50 to the pedestal 1. It will be obvious that the press body may be detachably secured as above described to any other suitable form of base, such as a work bench, table, or base plate.

55 The press body comprises an integral heavy metal casting of general rectangular form, the bottom wall 5 of which rests on the top plate 4 of the pedestal and is connected with the top wall 10 thereof by the 60 vertical integral side walls 11 and 12. The top wall 10 of the press body is provided with a flat under face 13 lying in a horizontal plane, and said wall forms the fixed head or platen of the press. The shiftable 65 head or bed of the press comprises a thick

oblong metal block 14 having flat upper and lower faces lying in parallel horizontal planes. The bed 14 is provided with reduced lateral extensions or guide portions 15 at opposite ends thereof slidable vertically in 70 guideways 16 formed in the inner faces of the thickened upper portions 11^a and 12^a of the side walls 11 and 12 of the press. The lower ends of the guideways 16 are open to permit ends 15 of the bed to be passed upwardly into the ways in assembling the 75 press. The bed is normally forced downward by a pair of coil springs 17 the upper ends of which are confined in sockets 118 formed in the platen 10.

80 The bed 14 is forced upwardly through the medium of a steel cam shaft 18 having two flat faces 19 and 20 at diametrically opposite points, cylindrical bearing portions 21 and 22, and a flattened end 23 adapted to engage in a socket 24 formed in one end of a hand-lever 25. A set screw 26, threaded through the wall of the socket end of the hand-lever, serves to detachably hold the lever on the end 23 of the cam shaft. The cam 18 is provided with two arcuate, diametrically opposed, working faces 27 and 28. The surface 27 is slightly eccentric to the axis of oscillation of the cam shaft which is coincident with the axial center of the 90 cylindrical bearing portions 21 and 22 of the shaft, while the surface 28 is concentric with the axis of rotation of the shaft and the outer surfaces of bearing portions 21 and 22. Surface 27 extends from edge *a* of flat face 100 19 to edge *b* of flat face 20 and rises gradually from *a* to *b*; while surface 28 extends from edge *c* of face 19 to edge *d* of face 20 on an arc struck from the center of the bearing portions 21 and 22.

105 The diameter of the bearing portions 21 and 22 is equal to the distance between faces 19 and 20 and also to the distance between the straight vertical sides of the vertically elongated bearings 29 and 30 in 110 walls 11 and 12 of the press body. Bearing 29 is in the form of a recess in wall 11, while bearing 30 is in the form of a slot or aperture in wall 12 through which the cam shaft is inserted endwise with its 115 flat faces perpendicular and then rotated to the position shown in Fig. 4, in assembling the machine. This arrangement prevents accidental displacement of the shaft and provides for direct vertical movement as well as axial rotation of the shaft when the lever 25 is operated. The inner edge of the socket 24 of the hand lever is formed with a lug or stop 31 adapted to engage stop shoulders or abutments 32 and 33 at 120 opposite ends of a segmental recess 34 formed in a boss 35 on the outer face of the wall 12 of the press body. The segmental recess, as shown in Figs. 8 to 10, is made sufficiently large to prevent binding of the 125 130

stop lug 31 owing to the vertical movement of the cam shaft and hand lever, and said stop lug in conjunction with abutments 32 and 33 serves to limit the extent of oscillation of lever 25 and the cam shaft from the position shown in Fig. 4 to that shown in Fig. 5.

The cam 18 is interposed between two rigid and relatively heavy flat plates 36 and 37 preferably formed of cold rolled steel. These thrust plates 36 and 37 are shifted edge wise in opposite directions by reason of their frictional contact with the cam shaft when the hand lever is operated. A set of antifriction rollers 38, preferably formed of cut lengths of cold rolled steel rods, is interposed between the upper face of plate 36 and the under face of the bed 14 of the press. A pair of steel wedge blocks 39 are slidably supported on a raised portion or track 40 formed on the upper face of the bottom wall 5 of the press body, said blocks being provided with depending side flanges or guides 41, and the under faces of said blocks being inclined in opposite directions at the same angle as the oppositely inclined faces 40^a of the track 40 upon which said blocks are slidably adjustable to vary the distance between the flat, horizontally disposed, upper or thrust-receiving faces of the blocks and the under face 13 of the fixed head or platen 10.

The blocks 39 are normally urged outwardly toward the lower ends of track 40 by a spring 42 coiled around a supporting rod 43 having its ends slidably confined in holes 44 bored in the inner ends of the blocks. The blocks are adjustable inwardly and outwardly by means of adjusting screws 45 threaded through the side walls 11 and 12 of the press body and having their inner ends engaging against the outer ends of the blocks. Blocks 39 form an adjustable thrust-receiving base or false bottom wall in the press body, and a set of antifriction rollers 46, similar to the rollers 38, are interposed between the flat upper faces of said blocks and the flat horizontally disposed under face of the thrust plate 37. The ends of the sets of rollers 38 and 46 are confined in retainers 47 formed by bending a metal strap to provide an elongated roller-end-embracing loop and a horizontal stop or projection 48. The ends of the bed 14 are cut away at the under side of the bed, as shown at 49 in Fig. 10, to provide clearances for the retainers 47, and the outer ends of plates 36 and 37 and blocks 39 terminate short of the inner faces of the side walls 11 and 12 for the same purpose.

The front and rear faces of the press body between the bed and bottom wall 5 are closed by detachable metal face plates 50 and 51 held to the press body by screws 52 and preferably countersunk in the press

body, as shown, to provide a flush construction. The lower portions of the front and rear faces of the bed 14 are also countersunk and these countersunk faces are overlapped by the upper portions of plates 50 and 51, whereby said plates assist in guiding the bed vertically and also keep the space between the bed and wall 5 closed in all positions of the bed. The stops 48 on the retainers 47 of the upper set of rollers 38, and the rear edge of the upper thrust plate 36, are normally urged rearwardly and held against the face plate 51 by a bowed spring 53. Spring 53 is secured midway its ends to the face plate 50 by rivets 54 and its ends are sufficiently wide to engage the front edge of plate 36 at all times, as shown in Figs. 4 and 5, and to engage the foremost roller 38 during the initial portion of the forward movement and final portion of the rearward movement of hand lever 25. The stops 48 on the retainers 47 of the lower set of rollers 46, and the front edges of plate 37, are normally held against the front face plate 50 by a bowed spring 55 the ends of which engage the rear edge of said plate 37 at all times and are adapted to engage the rearmost roller 46 during the initial forward movement and final portion of the rearward movement of hand lever 25. Spring 55 is secured to face plate 51 midway its ends by rivets 56. Springs 53 and 55 and stops 48 insure the return of the sets of rollers to the same positions after each operation of the press and said springs also serve in conjunction with the face plates to prevent creeping of the thrust plates 36 and 37.

A pair of plates 57, having their ends seated in horizontal grooves in the walls 11 and 12 of the press body, may be employed, if desired, to prevent the possibility of undue tilting of plate 36 in case the bed should be pulled or violently thrown up by a careless or mischievous person, especially when no type and cardboard and paper are in place on the carriage hereinafter described. These plates 57 may be omitted, however, as the construction and arrangement of parts are such that there is little possibility of substantial tilting of plate 36 and rollers 38 even under most unusual conditions.

It will be obvious that, since the lever 25 and cam 18 have a fixed throw, the closeness of the approach of the bed 14 to the face 13 of the platen 10 may be regulated by adjusting the wedge-like base blocks 39 along track 40. It will also be obvious that a relatively short forward movement of lever 25 will shift the flat faces 19 and 20 of cam 18 out of engagement with the plates 36 and 37 and place the advance portions of the faces 27 and 28 adjacent points *a* and *d*, respectively, in contact with said plates, thus imparting a relatively great and quick

initial rise to the bed 14. The remaining relatively long portion of the forward throw of the lever 25 will evidently cause a very slow and relatively slight additional rise 5 of the bed 14. It will also be obvious that we may employ a single long spring-pressed wedge block 39 and a single adjusting screw 45 for sliding said block on a track 40 inclined in one direction only from one side 10 wall of the press body to the other side wall, instead of the construction shown. It will also be obvious that springs 17 may be omitted, if desired, the bed 14 being returned by its weight alone.

15 A table or shelf for supporting cardboard, paper, type, finished cards, or the like, may be provided if desired. We have shown a detachable metal shelf or table 58 provided with an undercut socket or groove 59 at its 20 inner end having an open lower end, whereby said table may be attached to the press body by sliding the same downward to engage a dovetail projection or boss 60, formed on wall 11, in said socket 59.

25 A carriage, having a plurality of parallel longitudinally extending undercut ways, grooves or slots 61 therein, is slidably supported on the bed 14 to move longitudinally fore and aft of the press between the thickened upper portions 11^a and 12^a of the side walls 11 and 12 of the press body. The carriage is several times as long as the fore-and-aft width of the platen face 13 and bed 14 so that successive portions of the carriage 30 may be positioned between the bed and platen. For convenience and economy in manufacture, the slotted or grooved carriage is preferably formed by securing a plurality of relatively thick rigid metal bars 62 by 35 means of rivets 63, or in any suitable manner, to the upper face of a flat sheet metal plate 64. Bars 62 are secured to the plate with the downwardly and inwardly inclined or beveled longitudinal edges of the 40 bars spaced apart to form the slots or ways 61 parallel with the longitudinal center line of plate 64.

45 The plate or base 64 of the carriage rests upon and slides over the flat top face of bed 14 of the press and is slidably and detachably held to the bed, and guided to move directly fore and aft thereover, by means of a steel rod 65 having a sliding fit in a hole 66 bored horizontally through the bed 50 14 from front to rear midway the ends of the bed. Rod 65 may be inserted in, and withdrawn endwise from, the hole 66 when the carriage is detached therefrom. The carriage is attached to the guide and retaining rod 65 by inserting the reduced forward end 67 of the rod in a hole 68 formed in a flange or tongue 69, stamped downwardly from the forward end of plate 64, and then passing a screw 70 through a hole in the rear 55 end of plate 64 and screwing the same into

a threaded hole 71 bored vertically through rod 65. Flange 69 is stamped from the plate 64 close to the forward end of said plate and is of such length and width that a convenient hand grip 72 is formed at the 70 forward end of the carriage. It will be evident that, by the means described above, the carriage is held against movement in all directions relatively to the bed except fore and aft of the press.

75 Along each longitudinal edge of the carriage we provide retaining members or rails for type-holders. Each of these members is formed of sheet metal and provided with a horizontal web 73 connected by a vertical web 74 with an inwardly projecting transversely corrugated web 75 overhanging and spaced from the upper face of the adjacent outermost bar 62 on plate 64. Web 73 is secured by screws 76 to plate 64. The members or rails just described and the undercut grooves or slots 61 provide means whereby two different forms or styles of type-holders 77 and 78 may be detachably and 80 adjustably held to the carriage either separately or together to provide for "set-ups" 85 of many different forms. In Figs. 2, 4, 5, 13 and 14 we have shown three of the type-holders 77 mounted on the carriage, and in Fig. 19 we have shown a group composed of 90 two holders 77 and three holders 78 mounted on the carriage.

95 Both styles of type holders are formed of thin sheet metal and are of the same construction, except at their ends, comprising 100 flat bases or body portions provided along their forward and rear longitudinal edges with channel flanges 79 and 80. The channels in flanges 80 are deeper vertically than the channels in flanges 79, and the flanges 105 79 and 80 terminate short of the ends of the flat bottoms of the holders. Channel flanges 79 are adapted to receive only the relatively thin ledges 81 projecting laterally 110 from the lower edges of the punching or embossing type blocks 82, while channel flanges 80 are adapted to receive the thicker ledges 83 projecting laterally from the upper edges of the type blocks 82, whereby the 115 type blocks, which are inserted sidewise in the holders from the ends of the holders, can only be placed in the holders right side up or with the tops of the type all along the same longitudinal edge of the holder. The type faces are provided with the usual cutting 120 edges 84 adapted to penetrate the colored paper 85 and be forced partly through the cardboard backing 86.

125 The ends of the bottom portions of the type holders 77 are formed with integral 130 forwardly and upwardly extending spring tongues 87 having rounded transverse ribs 88 punched upwardly therefrom adjacent their free ends and adapted to snap into any one of the corrugations in rails 75 to retain 135

the holders in different adjusted positions on the carriage. Holders 77 are adjustable longitudinally of the carriage only, and may be detached from the carriage by sliding 5 said holders forwardly to withdraw their end portions from beneath the forward ends of the corrugated rails 75. Both styles of holders may be made in various widths to take different sizes of type blocks, and holders 10 78 may also be made of various lengths and are adjustable longitudinally and angularly on the carriage.

The ends of the holders 78 are formed with longitudinal slots 89 adapted to receive 15 the shanks of clamping bolts 90 inserted laterally in the open forward ends of the grooves 61 in the carriage. The heads 91 of bolts 90 have the shape of a four-sided pyramid to permit the bolts to slide freely 20 longitudinally of the grooves and prevent rotation of the bolts. Knurled thumb nuts 92 threaded on the shanks of the bolts serve to securely clamp the holders 78 in adjusted position on the carriage. It will be obvious 25 that holders 78 may be clamped to the carriage in different diagonal positions, in lines at right angles to the longitudinal center of the carriage or, by placing the bolts 90 at both ends of the holder in the same slot 61, 30 the holder may be clamped to the carriage on a line extending longitudinally of the carriage. Slots 89 are preferably formed at one side of the center line of holders 78 so that locking plates 93 each having a knurled 35 clamping screw 94 threaded through the center thereof, may be clamped to the holders close to the ends thereof when necessary. These rectangular locking and type-spacing plates or blocks 93 are each preferably 40 formed of sheet metal and has a raised or upwardly bent portion at one side thereof so that, when thumb screw 94 is tightened as shown in Fig. 16, the upper face of the block 93 will engage under the inwardly extending 45 edges of flanges 79 and 80 and the lower end of the screw will bind against the bottom of the holder, thus locking the block against movement longitudinally of the holder. Blocks 93 are employed with both 50 styles of holders at the ends of rows of type to retain the rows of type against longitudinal movement in the holders, and are also used to space words or groups of type in the holders. It will be obvious that other forms 55 of type spacers, such as blank type blocks may be employed, and that screws 94 may be omitted from the blocks 93 which are employed as spacers only.

The apparatus also includes a plurality 60 of card-holders or supports adjustably, detachably and yieldably held to the sliding carriage for supporting the cardboard backing 86 of the sign or other display card over the sheet, strips or pieces of colored paper 65 85 which are placed upon the faces of the

type 82 in the type-holders after the form or forms are set up. Each card holder comprises a light sheet metal angle bar 95 welded or otherwise rigidly secured adjacent its ends to the raised ends of a pair of light 70 angular spring metal supporting arms 96. The opposite or lower ends of arms 96 are detachably and adjustably clamped to the carriage by bolts 97, having pyramid heads similar to bolts 90 slidable in grooves 61 of 75 the carriage, and knurled clamping nuts 98.

We have shown two card-holders for each of the forms set up on the carriage in Figs. 13 and 19, but it will be obvious that either or both card-holders may be omitted. I 80 prefer to use at least one card holder, especially where the number or arrangement of the rows of type in the form is such that the cardboard backing 86 would tilt if supported only by the type blocks 82. The holders 95 are useful not only for supporting the cardboard backings, but also for aligning the top and bottom edges of the cardboard backing and preventing accidental shifting thereof. Where two holders are employed, 85 by setting them apart the width of the card 86 from top to bottom of the card, they facilitate final accurate arrangement of the type holders as they define on the carriage 90 the area of the card. 95

The upper faces of bars 62 are scored or grooved at regular intervals along parallel lines at right angles to the path of movement of the sliding carriage to form index lines 99 which cooperate with the parallel longitudinal grooves 61 to divide the carriage into uniform rectangular areas. These grooves 99 and 61 greatly facilitate accurate positioning of the type holders and card-holders and facilitate final longitudinal adjustment of the type blocks in the type holders. A pair of upstanding ears or lugs 100 are stamped up from plate 64 of the carriage adjacent the rear ends of bars 62 and are provided with vertically elongated bearing slots 101 for the ends of a hinge or pivot rod 102 around which is coiled or bent the rear end of a swinging sheet metal plate 103 of approximately the same length as bars 62. The hinge of plate 103 is preferably 105 located at a distance from screw 70 slightly greater than the width of the bed 14 from front to rear, so that when the carriage is drawn forward to the limit of its movement, defined by screw 70 engaging the 110 rear edge of the bed, said plate may be swung upward and rearward beyond a vertical position where it will be supported by the upwardly and rearwardly inclined front face of the platen 10, as shown in Fig. 2. 115

In the operation of the press, the wedge blocks 39 are adjusted to provide for the desired depth of penetration of the cutting edges of the type blocks 82 into the cardboard 86, the form or forms are set up on 120 125 130

the carriage, the piece or pieces of colored paper 85 are laid upon the type faces in the usual way with their adhesive coated sides uppermost, the cardboard backing 86 is then placed over the piece or pieces of paper with the upper and lower edges of the card seated on the angle iron bars 95, plate 103 is then swung forward and downward upon the backing card 86 to clamp the card and colored paper upon the faces of the type, the carriage is then shifted rearwardly to position all, or as much of the type as possible, between the bed and platen, the handle 25 is then pulled forward and downward its full stroke and returned to its initial position. If, owing to the number of forms set up on the carriage, or the size of the form, all of the type are not pressed into the paper by the first operation of the press, the carriage is then again shifted rearward and the handle 25 again operated. This is repeated until all the type have been forced through the colored paper into the cardboard backing or backings, whereupon the carriage is drawn forward, plate 103 swung upward, and the finished card or cards and surplus paper are removed. The card holders are free to yield downward relatively to the type during the embossing operation, and plate 103 is also free to move downward during the embossing operation owing to its vertical sliding and pivotal connection 101—102.

The structure above described provides an embossing press of small size and compact form adapted to develop a pressure of approximately twenty thousand pounds with little effort on the part of the operator. The structure shown also provides means whereby initial forward movement of the hand-lever 25 through approximately one-fourth of its throw will carry the surfaces 27 and 28 of the cam into engagement with the plates 36 and 37 and quickly lift the bed 14 three-fourths of its total rise, the final three-fourths forward throw of the hand lever causing surfaces 27 and 28 to ride over the plates 36 and 37 and slowly lift the bed 14 the last quarter of its rise. This arrangement permits adjustment of the press to quickly lift the plate 103 into contact with the platen face 13 by the first quarter stroke of the handle, and affords powerful leverage during the remaining three-quarters of the forward stroke of the handle for forcing the type through the paper 85 and partly into the cardboard 86.

It will be obvious that in making very elaborate ornamental signs requiring special type, or very irregular arrangements of type, the type blocks may be placed directly on the carriage, or may be attached by shellac or the like to a paper or metal sheet or plate placed on the carriage, the plate 103 serving to clamp the special form, card-

board, backing and paper in place on the carriage prior to the squeezing operation of the press.

What we claim is:

1. In an embossing press, the combination of a base member, a platen member, a pair of upright side members rigidly supporting the platen member a fixed distance above the base member, said upright side members having vertically elongated shaft-bearings therein intermediate their ends and being provided with vertical guide channels in the inner faces thereof above said bearings, a cam shaft supported in said bearings for rotary and vertical movements, horizontally disposed thrust plates arranged above and below the shaft and shiftable both vertically and fore and aft of the press between said upright side members, spring means normally urging one plate forwardly and the other plate rearwardly, means for limiting the extent of movement of the plates by said spring means, a vertically shiftable bed member under the platen having side extensions slidably confined in the guide channels in the upright members, a series of antifriction rollers interposed between said bed member and the uppermost thrust plate and extending transversely of the press between said side members and movable bodily vertically with said thrust plate, a series of antifriction rollers extending transversely of the press under the lowermost thrust plate between said side members and movable bodily vertically, supporting means for said last-mentioned series of rollers slidably mounted on said base member under said series of rollers, said supporting means and base having inclined engaging faces, means for adjusting said supporting means on the base to shift the bed member together with the rollers and thrust plates and cam shaft vertically and thereby change the normal relation between the bed member and platen, and means connected with the cam shaft for oscillating the shaft to move the bed member toward and from the platen.

2. In an embossing press, the combination of a base member, a platen member, a pair of upright side members rigidly supporting the platen member a fixed distance above the base member, said upright side members having vertically elongated shaft-bearings therein intermediate their ends and being provided with vertical guide channels in the inner faces thereof above said bearings, a cam shaft supported in said bearings for rotary and vertical movements, horizontally disposed thrust plates arranged above and below the shaft and shiftable both vertically and fore and aft of the press between said upright side members, spring means normally urging one plate forwardly and the other plate rearwardly, means for limit-

- ing the extent of movement of the plates by said spring means, a vertically shiftable bed member under the platen having side extensions slidably confined in the guide chan-
 5 nels in the upright members, a series of antifriction rollers interposed between said bed member and the uppermost thrust plate and extending transversely of the press be-
 10 tween said side members and movable bodily vertically with said thrust plate, a series of antifriction rollers extending transverse-
 15 ly of the press under the lowermost thrust plate between said side members and movable bodily vertically, supporting means for
 20 said last-mentioned series of rollers slidably mounted on said base member under said series of rollers, said supporting means and base having inclined engaging faces, means for adjusting said supporting means on the base to shift the bed member together with the rollers and thrust plates and cam shaft vertically and thereby change the normal relation between the bed member and platen, a lever connected with the cam shaft
 25 at one end thereof for oscillating the shaft to raise and lower the bed member, and co-
 operating stops on said lever and the adjacent upright member for limiting the throw of said lever.
- 30 3. In an embossing press, the combination of a fixed platen, a vertically shiftable bed under the platen, a cam under the bed, means for rotatably and slidably supporting the cam to oscillate about a horizontal axis
 35 and move bodily up and down, means for guiding the bed to move vertically, means for oscillating the cam, a pair of horizontally disposed floating thrust plates above and below the cam and engaged thereby,
 40 antifriction rollers interposed between the bed and upper thrust plate, antifriction rollers under the lower thrust plate, a pair of supporting members located under different end portions of said last mentioned rollers,
 45 and means for independently adjusting said supports vertically.
4. In a press, the combination of a base having two oppositely inclined wedge block tracks thereon extending transversely of the
 50 press and arranged end to end, a pair of wedge blocks arranged end to end on said tracks having horizontally disposed flat upper faces and inclined lower faces slidably engaging said tracks, means for adjusting
 55 the blocks endwise on the tracks, a vertically movable bed above said blocks, a cam shaft extending transversely of the press between the bed and said blocks, a pair of horizontally disposed thrust plates located above
 60 and below the cam shaft and engaged thereby, a series of antifriction rollers extending transversely of the press between the upper plate and bed, a series of antifriction rollers extending transversely of the press between the lower plate and said blocks, means guid-
 65 ing the cam shaft to oscillate about a horizontal axis and move bodily vertically, means for oscillating the cam shaft, and a fixed platen above the bed.
5. In a press, the combination of a base having two oppositely inclined wedge block tracks thereon extending transversely of the press and arranged end to end, a pair of wedge blocks arranged end to end on said tracks having horizontally disposed flat upper faces and inclined lower faces slidably engaging said tracks, means for adjusting the blocks endwise on the tracks, a vertically movable bed above said blocks, a cam shaft extending transversely of the press between the bed and said blocks, a pair of horizontally disposed thrust plates located above and below the cam shaft and engaged thereby, a series of antifriction rollers extending transversely of the press between the upper plate and bed, a series of antifriction rollers extending transversely of the press between the lower plate and said blocks, means guiding the cam shaft to oscillate about a horizontal axis and move bodily vertically, means for oscillating the cam shaft, a fixed platen above the bed, and means for limiting the extent of oscillatory movement of the cam shaft by said shaft oscillating means.
6. In a press, the combination of a base having two oppositely inclined wedge block tracks thereon extending transversely of the press and arranged end to end, a pair of wedge blocks arranged end to end on said tracks having horizontally disposed flat upper faces and inclined lower faces slidably engaging said tracks, means for adjusting the blocks endwise on the tracks, a vertically movable bed above said blocks, a cam shaft extending transversely of the press between the bed and said blocks, a pair of horizontally disposed thrust plates located above and below the cam shaft and engaged thereby, a series of antifriction rollers extending transversely of the press between the upper plate and bed, a series of antifriction rollers extending transversely of the press between the lower plate and said blocks, means guiding the cam shaft to oscillate about a horizontal axis and move bodily vertically, means for oscillating the cam shaft, a fixed platen above the bed, and spring means interposed between the adjacent ends of said wedge blocks for normally urging the blocks toward opposite sides of the press.
7. An embossing apparatus comprising a bed member, a platen member over the bed member, a long type and work support mounted on the bed member to shift longitudinally in a horizontal plane over the bed member, said platen member being relatively narrow longitudinally of the support and said support having a long flat upper surface for supporting type with the type faces

uppermost over an area substantially greater than the area of the under pressure face of the platen member, a long flat work-clamping device, means connecting said clamping device with said support for movement to and from a clamping position overlying the type-supporting surface of said support in which said clamping device is adapted to engage the upper side of work sheets placed over and supported on the faces of type mounted on the support, and means for imparting relative vertical rectilinear movements between said members with the support in various horizontally shifted positions.

8. An embossing apparatus comprising a bed member, a platen member over the bed member, a long type and work support mounted on the bed member to shift longitudinally in a horizontal plane over the bed member, said platen member being relatively narrow longitudinally of the support and said support having a long flat upper surface for supporting type with the type faces uppermost over an area substantially greater than the area of the under pressure face of the platen member, a long flat work-clamping device, means connecting said clamping device with said support for movement to and from a clamping position overlying said type-supporting surface of said support and in which said clamping device is adapted to engage the upper side of work sheets placed over and supported on the faces of type mounted on the support, and means for raising and lowering the bed with the support in various horizontally shifted positions to subject different portions of work to pressure.

40 9. An embossing apparatus comprising a bed member, a platen member above the bed member, a long type and work support mounted on the bed member to move endwise horizontally relatively to the bed and platen members, said platen member being relatively narrow longitudinally of the support and said support having a long flat upper surface for supporting type-forms face up with work sheets overlying the type faces, and means for moving the bed member vertically toward and from the platen member with the support thereon in various longitudinally adjusted positions, whereby work over the entire long type-form supporting surface of the support may be brought under the narrow platen member by successive longitudinal movements of said support and subjected to pressure between the bed member and said narrow platen member by shifting the bed member toward and from the platen member after each longitudinal movement of the support.

60 10. An embossing apparatus comprising a bed member, a platen member above the bed member, a long type and work support

mounted on the bed member to move endwise horizontally relatively to the bed and platen members, said platen member being relatively narrow longitudinally of the support and said support having a long flat upper surface for supporting type-forms face up with work sheets overlying the type faces, means for moving the bed member vertically toward and from the platen member with the support thereon in various longitudinally adjusted positions, whereby work over the entire long type-form supporting surface of the support may be brought under the narrow platen member and subjected to pressure between the bed member and said narrow platen member, and means shiftably held to said support for holding work against the faces of type carried by the support.

11. In a press, the combination of a base having an inclined upper surface, a block having a flat upper face and an inclined lower face slidable on the inclined surface of the base, means for adjusting the block along the inclined surface of the base, a vertically movable bed above said block, a cam shaft between the bed and block, a pair of oppositely shiftable thrust plates located above and below the cam shaft and engaged thereby, a set of antifriction rollers between the upper plate and the bed, a set of antifriction rollers between the lower plate and said block, means supporting the cam shaft to oscillate and move vertically, means for oscillating the cam shaft, a fixed platen above the bed, said cam having two oppositely disposed parallel flat faces normally engaging the thrust plates and connected by two arcuate faces one of which is concentric with the axis of the shaft and the other slightly eccentric to the axis of the shaft.

12. An embossing apparatus comprising a bed member, a platen member above the bed member, a long type and work support mounted on the bed member to move endwise horizontally relatively to the bed and platen members, said platen member being relatively narrow longitudinally of the support and said support having a long flat upper surface for supporting type-forms face up with work sheets overlying the type faces, means for moving the bed member vertically toward and from the platen member with the support thereon in various longitudinally adjusted positions, whereby work over the entire long type-form supporting surface of the support may be brought under the narrow platen member and subjected to pressure between the bed member and said narrow platen member, and a long flat work-clamping plate pivotally held to said support to swing to and from a horizontal work-engaging position overlying the type-carrying face of the support.

13. In an embossing press, the combination of a platen, a vertically movable bed under the platen, a cam shaft under the bed, means supporting the shaft to oscillate and move vertically, means for oscillating the shaft, laterally movable thrust plates above and below the shaft, said cam shaft having oppositely disposed flat faces normally engaging the thrust plates and connected by two arcuate faces one of which is concentric with and the other eccentric to the axis of the shaft, a set of antifriction rollers between the upper thrust plate and the bed, a set of antifriction rollers under the lower thrust plate, and a support over which the lower set of rollers travels.
14. An embossing apparatus comprising a bed member, a platen member above the bed member, a long type and work support mounted on the bed member to move endwise horizontally relatively to the bed and platen members, said platen member being relatively narrow longitudinally of the support and said support having a long flat upper surface for supporting type-forms face up with work sheets overlying the type faces, means for moving the bed member vertically toward and from the platen member with the support thereon in various longitudinally adjusted positions, whereby work over the entire long type-form supporting surface of the support may be brought under the narrow platen member and subjected to pressure between the bed member and said narrow platen member, a long flat work-clamping device, and means connecting said device with the support to permit swinging movements of the device to and from a horizontal work-clamping position overlying the support and to also permit relative vertical movements between said device and said support while superposed when subjected to pressure between the bed and platen members.
15. In an embossing press, the combination of a bed, a fixed platen above the bed, means for shifting the bed vertically toward and from the platen, said bed and platen being relatively narrow fore and aft of the press and said bed having a horizontal guide passage therethrough extending fore and aft of the press, a long type and work carrier extending fore and aft of the press and slidably resting on the upper face of the bed, a long and rigid guiding and retaining member extending through said passage in the bed and reciprocable therein fore and aft of the press, and means connecting said member with said carrier to move fore and aft of the press in unison with the carrier.
16. In an embossing press, the combination of a bed, a fixed platen above the bed, means for shifting the bed vertically toward and from the platen, said bed and platen being relatively narrow fore and aft of the press and said bed having a horizontal guide passage therethrough extending fore and aft of the press, a long type and work carrier extending fore and aft of the press and slidably resting on the upper face of the bed, a long and rigid guiding and retaining member extending through said passage in the bed and reciprocable therein fore and aft of the press, and means connecting said member with said carrier to move fore and aft of the press in unison with the carrier.
17. In an embossing press, the combination of a bed, a fixed platen above the bed, means for shifting the bed vertically toward and from the platen, said bed and platen being relatively narrow fore and aft of the press and said bed having a horizontal guide passage therethrough extending fore and aft of the press, a long type and work carrier extending fore and aft of the press and slidably resting on the upper face of the bed, a long and rigid guiding and retaining member extending through said passage in the bed and reciprocable therein fore and aft of the press, and means connecting said member with said carrier to move fore and aft of the press in unison with the carrier, said carrier being adapted to support type forms face up on its upper surface throughout the greater portion of its length, and a long work-clamp hinged to said carrier adjacent the rear end of the carrier to swing forwardly and downwardly over the carrier to hold work sheets over type on the carrier, said clamp being movable to an upwardly and rearwardly inclined position in which it is supported against the forward edge of the platen when the carrier is drawn forward.
18. In an embossing apparatus, the combination of a platen, a bed, means for imparting a relative vertical movement between the bed and platen, a form-supporting carriage slidably held to the bed to move horizontally, and a plate movable toward and from the upper face of the carriage and held to said carriage.
19. In an embossing apparatus, the combination of a platen, a bed, means for imparting a relative vertical movement between the bed and platen, a form-support-

ing carriage slidably held to the bed to move horizontally, and a plate pivotally held at one end to the carriage to move toward and from a form on the carriage.

20. In an embossing apparatus, the combination of a platen, a bed, means for imparting a relative vertical movement between the bed and platen, a form-supporting carriage slidably held to the bed to move horizontally, and a plate having a pivotal and vertically slidable connection at one end with the carriage adjacent the rear end of the carriage.

21. In an embossing apparatus, the combination of a platen, a bed, means for imparting a relative vertical movement between the bed and platen, and a form-supporting carriage slidably held to the bed to move horizontally, said carriage being provided with indicating means for facilitating the arrangement of type thereon.

22. In an embossing apparatus, the combination of a platen, a bed, means for imparting a relative vertical movement between the bed and platen, and a form-supporting carriage slidably held to the bed to move horizontally, said carriage being divided into sections of uniform area by longitudinal and transverse grooves.

30. 23. In an embossing apparatus, the combination of a platen, a bed, means for imparting a relative vertical movement between the bed and platen, a form-supporting carriage slidably held to the bed to move horizontally, type block holders, and means for clamping said holders in angularly adjusted positions on the carriage.

24. In an embossing apparatus, the combination of a platen, a bed, means for imparting a relative vertical movement between the bed and platen, a form-supporting carriage slidably held to the bed to move horizontally, said carriage being provided with longitudinal undercut channels, clamping bolts having their heads confined in said channels, type-holders on the carriage having longitudinal slots at their ends through which the shanks of said bolts extend, and clamping nuts threaded on said bolts above the ends of the type-holders.

55. 25. In an embossing apparatus, the combination of a platen, a bed, means for imparting a relative vertical movement between the bed and platen, a form-supporting carriage slidably held to the bed to move horizontally, longitudinally extending side rails on the carriage provided with transversely corrugated portions overhanging the upper face of the carriage, and type-holders on the carriage provided with spring tongues at their ends engaging in the corrugations on the under side of the overhanging portions of said side rails.

60. 26. A type-form carrier for embossing presses comprising a flat supporting mem-

ber having parallel side edges and provided with uniformly spaced transversely extending parallel type-holder aligning and spacing indicating grooves in its upper face at right angles to the side edges thereof, a plurality of straight transversely extending type-block holders slidable over the grooved face of said member, means along the side edges of said supporting member forming inwardly facing channels, and means at the ends of said holders engaging in said channels for frictionally retaining the holders in any desired spaced relation on the support at right angles to the side edges of the support.

70. 27. A type-form and work sheet holder for embossing presses, comprising a member having a flat type-form supporting face adapted to support a form with the type faces uppermost, and means carried by said support for yieldably supporting a cardboard work sheet over a form at two opposite edges of said sheet.

75. 28. A form-supporting carriage for embossing presses comprising a form-sustaining bed and a plate hinged at one end to the carriage to swing toward and from the form-sustaining bed.

80. 29. A form-supporting carriage for embossing presses having card-edge supporting devices adjustably and yieldably mounted thereon.

85. 30. In embossing apparatus, the combination of a form-support, and a card-edge support adjustably mounted on the form support.

90. 31. In embossing apparatus, the combination of a form-support, a pair of card-edge supporting bars of angular form in cross section, resilient supporting members held 105 to said bars, and means for detachably and adjustably holding said members to the form-support.

95. 32. A type-block holder for embossing presses having resilient fingers at its ends, 110 for the purpose set forth.

100. 33. A sheet metal type-block holder for embossing presses comprising a flat base having longitudinal edge flanges of channel form terminating short of the ends of the 115 base, the ends of said base having resilient locking fingers stamped up therefrom.

105. 34. In an embossing apparatus, the combination of a platen, a bed having a hole extending horizontally therethrough fore and aft of the bed, means for imparting a relative vertical movement between the bed and platen, a slideable rod extending through the hole in the bed and of greater length than the width of the bed, and a form-support 120 slidably resting on the bed and held to said rod.

110. 35. In embossing apparatus, the combination of a type-holder having longitudinal edge flanges of channel form, one of said 125

flanges being deeper than the other, a type-retaining plate of less thickness than the depth of the shallower flange and having the edge portion thereof engaged in the deeper flange offset above the main body portion of the plate, and a clamping screw threaded through the center of said plate against the base of the holder for forcing the plate up-

ward into engagement with the overhanging walls of the channel flanges. 10

In testimony whereof we hereunto affix our signatures.

HARRY M. SEAGERS.
